UNITED STATES PATENT OFFICE.

PHILLIP SCHNEIDER, OF GARNER, IOWA.

KITCHEN-CABINET.

SPECIFICATION forming part of Letters Patent No. 582,697, dated May 18, 1897.

Application filed January 18, 1897. Serial No. 619,622. (No model.)

To all whom it may concern:

Be it known that I, PHILLIP SCHNEIDER, a citizen of the United States, residing at Garner, in the county of Hancock and State 5 of Iowa, have invented a new and useful Kitchen-Cabinet, of which the following is a specification.

This invention relates to that class of kitchen-cabinets designed to contain a number of 10 articles used in making food-stuffs and to provide means whereby dough, &c., may be conveniently and easily compounded and kneaded and to provide a means whereby leavened food-stuffs may be subjected to the 15 proper conditions necessary for it to rise.

The object is, primarily, to provide simple, cheap, and convenient means whereby flour may be easily and quickly placed in a receptacle within the cabinet, where it may be conveniently used and ready access be had to 20 said receptacle or hopper either when full or empty, and, further, to provide means whereby flour may be easily and quickly taken from the hopper and passed through a sieve to the 25 mixing-board.

My invention consists in the construction, arrangement, and combination of the hopper and the means for operating same with the sieve and the other parts of the device, as 30 hereinafter set forth, pointed out in my claims, and illustrated in the accompanying drawings, in which—

Figure 1 shows a vertical central section of the complete cabinet. Fig. 2 shows a detail 35 perspective of the movable hopper. Fig. 3 shows a front view of the complete cabinet with the cabinet-doors open.

Referring to the accompanying drawings, the reference-letter A is used to indicate the 40 exterior of the cabinet, and A² and A³ two horizontal partitions to divide the cabinet into three compartments. The fronts of the upper and lower compartments are covered by doors B, hinged at their outer sides, and 45 B² indicates a combined door and table hinged at its lower edge to the central partition to swing outwardly to a horizontal position, where it is supported by chains B³, and may be used as a table on which dough may be 50 compounded and kneaded.

In the lower compartment is a hinged shelf C, supported at its outer end by chains C².

On the interior of the cabinet and resting upon its bottom I have provided a sheet-metal casing into which a lamp may be placed 55 to furnish heat on the interior of the cabinet to aid in raising the breadstuffs within the cabinet.

In the upper compartment I have provided two drawers D D at the opposite sides thereof, and between these drawers is a sliding platform D², hinged at its central portion, so that when the platform is drawn out its outer portion may fold down. The sides of the platform are tongued at D³ to enter grooves D⁴ 65 in the strips D⁵, which are secured to the upper partition to hold said platform in place.

D⁶ indicates a spring-catch on one of the strips D⁵ to enter a notch in the rear section of the platform, and thus prevent the platform from sliding out too far.

F indicates a hopper designed to contain flour and having its sides and back inclined inwardly toward the base, so that it may rest on the front half of the platform.

F² indicates the top of the hopper, of which the rear section is hinged at its rear end to swing rearwardly.

F³ indicates a slide-valve in the bottom of the hopper to cover an opening in the bottom 80 and in the platform.

A chain F⁴ is attached to the rear upper corners of the hopper and to the back of the compartment to limit the movement of the hopper when it swings outwardly.

J indicates a brace secured to the platform to engage the rear face of the hopper and prevent it from falling rearwardly.

K indicates a collar secured to the under side of the upper partition A² to coincide with 90 an opening therein, and K² indicates a sieve detachably secured to the collar.

When the hopper is in place and the sieve in its bottom opened, the flour from the hopper may freely pass to the sieve.

It is obvious that when the hopper is drawn out access may readily be had to all parts thereof either for cleaning or filling it and that when in position in the machine any desired quantity of flour may be taken from the 100 hopper and passed through the sifter to the mixing board or table.

Having thus described my invention, what I claim as new therein, and desire to secure by

Letters Patent of the United States therefor, is—

1. In a kitchen-cabinet the combination with a frame, a partition near its top, a flour-
5 sieve under an opening in the partition, a slide on top of the partition hinged at its central portion, a stop for limiting the outward movement of the slide, a hopper on the slide, a valve in the hopper, and chains for limiting the movement of the hopper for the purposes stated.

15 2. A kitchen-cabinet comprising a casing, two horizontal partitions therein, a heater in the lower compartment, a hinged front to the middle compartment to serve as a mixing-

table, a sieve mounted below an opening in the upper partition, grooved strips on top of the upper partition, a tongued platform to slide in said grooves, and hinged at its central portion, a spring-catch to limit the outward movement of the slide, a hopper fixed to the outer section of the slide, a top to the hopper having a rear section thereof hinged and chains for limiting the movement of the hopper, substantially as and for the purposes 25 stated.

PHILLIP SCHNEIDER.
